UNITED STATES PATENT OFFICE.

ROBERT W. SCOTT, OF BABYLON, NEW YORK, ASSIGNOR TO SCOTT AND WILLIAMS,
INCORPORATED, OF NEW YORK, N. Y., A CORPORATION OF MASSACHUSETTS.

KNITTING-MACHINE.

1,373,358.

Specification of Letters Patent. Patented Mar. 29, 1921.

Application filed March 4, 1920. Serial No. 363,134.

To all whom it may concern:

Be it known that I, ROBERT W. SCOTT, a citizen of the United States of America, residing in Babylon, in the county of Suffolk, 5 in the State of New York, have invented certain new and useful Improvements in Knitting-Machines, of which the following is a specification.

My invention relates to rotary knitting machines employing spring beard needles or other needles of the latchless type, by which term I mean to exclude needles employing the usual pivoted latches and to include needles employing slides in connection with the hooks of the needles. For example, 10 British Patent 3774 of 1880 illustrates several forms of knitting needles with slides.

In knitting machines employing beard needles or other latchless needles, it is quite 20 difficult to secure the feeding of the yarns so as to be surely engaged by the hooks of the needles. My invention consists in providing means whereby this difficulty is overcome.

25 In the accompanying drawings—

Figure 1 is a sectional elevation of sufficient of a rotary knitting machine to illustrate my invention;

Fig. 2 is an end view, looking at the left 30 of the upper part of Fig. 1;

Fig. 3 is a view illustrating the relation of the yarn-feeding finger to another form of needle.

Referring to Fig. 1, I have there shown 35 my invention as applied to a rotary knitting machine of the type in which pivoted yarn fingers are employed in any suitable manner, 8 being the throat plate on which the feeding ends of the yarn fingers rest when in 40 active position to supply yarn to the circle of needles.

The type of latchless needle N shown in 45 this Fig. 1 is a spring beard needle which as is well known, requires special appliances and modes of operation or special locating 50 of the feeding point in relation to the knitting point in order to get the yarn safely under the points of the beards. I accomplish the result successfully by combining 55 with the latchless needle a particular construction and operation of yarn feeding finger. In the drawing I have shown only two pivoted fingers F, F¹, but as many such fingers may be employed as occasion may require. In the first place the feeding end of

the yarn finger is beveled off at γ to give a reduced forward end, and the hole α through which the yarn is threaded, has its outlet at the extreme forward end of the yarn finger adjacent the needles. 60

Each of these yarn fingers is so pivoted to the frame on which it is mounted that the yarn finger will move in a plane parallel with the length of the needle and may have a compound movement, namely, a pivoting 65 movement to bring its feeding end into and out of active position and also a bodily movement toward and from the circle of needles. For this purpose the fingers are slotted at 6 where they are pivoted upon a cross-pin 70 5, which may be mounted in the arch 4, forming a part of the latch ring 10 or other suitable part of the frame.

Spiral springs 13 connected at one end to the cross bar 14 and at the other end to hooks 75 12 on the yarn fingers F, F¹ tend to draw the yarn fingers bodily away from the circle of needles as far as the slots 6 will permit, and also tend to draw the yarn feeding ends of the fingers to the active or feeding position as shown in the case of the finger F in Fig. 1. The elevation of the fingers to the inactive position as shown in the case of the yarn fingers F¹ is accomplished by suitable thrust bars 20 actuated at the appropriate 85 times by a cam cylinder as described in my Patent No. 1,238,052, dated August 21, 1917, for example.

The yarn fingers have their extreme rear ends beveled or cammed at 7, and in an overhanging bracket 16, which may be secured to the arch 4, are provided adjustable bearing screws 17, one in line with each yarn finger. When a thrust bar 20 drops to allow the spring 13 to snap the forward end of the 90 yarn finger down from the position F¹ to the active position F, the beveled or cammed rear end of the yarn finger will strike the bearing screw 17 with the result that after the forward end of the finger has passed the 95 tops of the needles in the downward swinging movement of the finger, that forward end will be thrust outwardly toward the needle shanks and under the hooks of the needles. The reducing of the end of the 100 yarn finger, as shown, permits this thrusting of the finger end and of the yarn which comes out of the forward end thereof, directly under the hooks of the needles. Accordingly the taking of the yarn by the 110

needle hooks is thus assured without the use of any other special appliances and without undue separation between the feeding point and the knitting point in the circle of needles.

In Fig. 3 I have indicated a type of needle N¹, wherein a slide n takes the place of the ordinary pivoted latch. It will be seen that by reason of the backward bend given to the 10 needle adjacent the hook, it would be extremely difficult to feed the yarn to the hook without the use of the yarn finger with reduced end delivering the yarn at its outer end and means to thrust that outer end and 15 the yarn under the hook.

I claim as my invention:

A knitting machine comprising knitting needles of other than the pivoted latch type in combination with a pivoted yarn finger pivoted to move in a plane parallel with the 20 length of the needles and having a reduced outer end delivering the yarn at such outer end in combination with means to thrust such reduced outer end under the hooks of the needles when the yarn finger is moved 25 to active position.

In testimony whereof I have signed my name to this specification.

ROBERT W. SCOTT.
